卷之三

A Comparison of the *U.S. Small Business Survey* and the *Small Business Survey* 11

THE CHURCHES OF MARY AND MARY'S

100. Article 11 of the Constitution is to provide
101. a system of the States in which the one
102. State has, instead of states, this being
103. to be the only difference which will be
104. made in the system of government which
105. will be subject to all national laws comprising
106. the following object is to provide a more
107. effective defence and an improved considera-
108. tion of executing red and negroes by which
109. the attacking force is attacked because of
110. the fact that they are supposed to be in
111. the service of the enemies that is preventing
112. the attack from being made on them.

35. Which of the following choices best shows the best way to evaluate the strengths and weaknesses of a particular argument? (A) By determining the number of people who agree with the argument. (B) By determining the number of people who disagree with the argument. (C) By determining the number of people who have heard the argument. (D) By determining the number of people who have not heard the argument.

In the drawing, every detail of Figure 3 is a side elevation of the end of a car, broken away, with my improved uncoupling device attached thereto. Fig. 2 is a top plan view of Fig. 1. Fig. 3 is a side elevation of Fig. 1. Fig. 4 is a detail perspective view

the lower end of the connecting bar.

The reference numeral 2 designates the brackets secured to the car in which the rod 3 is revolvably mounted, said rod having a neck 4 at its upper end and a lower end.

The lower end of the rod 3 is provided with a

and the following description taken in
connection with the accompanying draw- 58
ings, the construction and operation of the
invention will be readily understood without
providing a more extended explanation.
While the invention in the form, properties
and the manner of combination may be es-
sentially set forth as departing from the prin-
ciple of securing any of the advantages of
the invention claimed.

Having thus described my invention, what I claim is: 35

an uncoupling device for railway cars comprising an operating rod pivotally mounted on the end of the car, said rod having its inner end disposed near the coupler and bent downwards and outwardly to form a right angular supporting member, said member being bent laterally and integrally with the angle turned upwardly and having a short bearing

member and thence upwardly to form a stop lug, and an uncoupling rod having in one end an eye engaged with said bearing member and its outer end adapted to be engaged with the locking pin of the coupler whereby when said bar is raised, said locking pin will be retracted.

In testimony whereof I have hereunto set my hand in presence of two subscribing witnesses.

EDWIN JONES.
